[57] CLAIM

The ornamental design for a dresser or the like, as shown and described.

DESCRIPTION

FIG. 1 is a front elevational view of a dresser or the like showing our new design, the rear of the dresser being substantially flat and unornamented;

FIG. 2 is a right side elevational view thereof, the opposite side being substantially a mirror image thereof; and

FIG. 3 is a top plan view.

FIG.2
